UNITED STATES PATENT OFFICE.

GEORGE A. AMBLER, OF NEWARK, NEW JERSEY.

COMBINED SINGLE AND DUPLEX NAILING-MACHINE.

SPECIFICATION forming part of Letters Patent No. 548,343, dated October 22, 1895.

Application filed February 4, 1895. Serial No. 537,150. (No model.)

To all whom it may concern:

Be it known that I, GEORGE A. AMBLER, a citizen of the United States, residing at Newark, in the county of Essex and State of New Jersey, have invented certain new and useful Improvements in a Combined Single and Duplex Nailing-Machine; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My present invention relates to improvements in machines for uniting the soles and uppers of boots and shoes by means of fastenings composed of wire which are fed into the stock to be united and then cut off.

20 In a patent granted to me August 28, 1894, No. 525,066, I have shown and claimed a device to be used in connection with machinery of this class for feeding and inserting two such fastenings simultaneously, either in a 25 continuous row or in two parallel rows, into the stock presented.

The present invention has for its object to provide for use in connection with machines in which two coils of wire are used and in 30 which a "working head" is employed to convert the machine into a duplex nailing-machine mechanism by means of which only one fastening may be inserted in the stock at each actuation of the machine, or two such 35 fastenings may be simultaneously fed and inserted into the stock at each actuation, as necessity may require.

The invention therefore consists in the novel arrangements and combinations of 40 parts to be hereinafter more fully described, and finally embodied in the clauses of the claim.

I have illustrated my improvements in connection with a nailing-machine of the type 45 illustrated in Letters Patent No. 325,274, of September 1, 1885; but it is applicable to other forms of nailing-machines.

In the drawings, Figure 1 is a front elevation of a nailing-machine provided with the 50 mechanism embodying the principles of my invention. Fig. 2 is a front elevation of the working head and other parts connected

therewith with my improvement applied thereto on a larger scale to more clearly illustrate the nature of my invention; and Fig. 3 is a left-hand side elevation of the said parts represented in said Fig. 2. Fig. 4 is an edge view, and Fig. 5 a face view, of a lever and operating mechanism connected therewith. Fig. 6 is a detail front view of a wire-gripping device used in connection with my invention, and Fig. 7 is a section taken on line z in said Fig. 6.

Similar letters of reference are employed in each of the above-described views to indicate corresponding parts.

In said drawings, A is the frame of the machine, of proper shape to support the various parts, provided with suitable bearings for the main shaft a , having thereon suitable pulleys a' and a'' for receiving the driving-belt.

The several parts of the structure represented in Figs. 1, 2, and 3 of the drawings, which are old, are the working head and its driving-sleeve B, which is preferably of the 75 construction shown in my previous patent, No. 525,066, which converts the nailing-machine into a duplex nailing or fastening device. Other parts that are old in themselves are the hollow spindle b and its extension, 80 the knuckle-piece a^3 , the pitman a^4 , which is pivoted or jointed by a pin a^5 directly to a collar a^6 , which is attached to or forms part of the driving-sleeve operating the grippers of the working head, so that the pitman im- 85 parts a uniform reciprocatory movement to said working head. Other old features are the yoke a^7 , having its fulcrum upon a vertical rod a^8 , held rigidly by the framework A.

The other parts of the machine, which are 90 old in themselves, need not be further described in connection with my present invention, since the working thereof will be clearly understood from an inspection of the drawings and specification of said Letters Patent No. 325,274; but it must be borne in mind that the parts within the said driving-sleeve B are of the construction shown in my previous patent, No. 525,066, for a device for feeding and inserting two fastenings simultaneously, these parts being of such a construction as to readily permit the revolutions of the spindle when the machine is working as a duplex machine and still not interfering with

the feeding of the two wire strands from which the fasteners are cut by the knives or cutters beneath said working head. The present machine being intended for use either as a single or a duplex nailing-machine, when it is used to drive two wire slugs simultaneously the wires are forced into the material by the grippers of the working head illustrated in my said Patent No. 525,066, and are cut off without the quarter-turn given to the single wire when the machine is used as a single nailing-machine.

My present invention relates to certain novel arrangements and combination of parts in combination with these parts, old in themselves, whereby the machine may be used as a single or a duplex nailing-machine.

The new features consist, essentially, of a suitable frame *c*, secured on the top of the frame *A* by means of screws or bolts *c'*, being provided with ways or guides *c²*, in which is movably arranged to slide up and down in said frame *c* a slide or cross-head *d*, provided with a gripping device *d'*, the construction and operation of which will be more fully described hereinafter. Said slide *d* receives its upward or downward movements by means of two pivotally-connected arms *e* and *f*. The lower and longer arm *e* is pivotally arranged on a pin *a⁹* on the collar of the driving-sleeve *a⁶*. The upper arm *f* is pivotally connected by means of a pin *f'* to said slide or cross-head *d* and is provided with a nosing or suitable cam-like projection *f²*.

When it is desired to use the machine as a single nailing machine, the two arms *e* and *f* are in a straight line, as clearly shown in Fig. 1, thereby causing the nosing *f²* on the arm *f* to be forced tightly against the gripping-plate *d³*. Said plate *d³* slides in the ways or guides *d⁵* on the side of the cross-head *d* and is provided with suitable teeth or serrations *d⁴*, which are brought against the wire *g*, thereby firmly pressing the same against the teeth or serrations *d⁷* of the fixed gripping-plate *d⁶*, as clearly shown in Figs. 6 and 7. Said last-mentioned plate *d⁶* may be formed integral with the slide or cross-head *d* or may be secured thereto by screws *d⁸*. When the gripping device *d'* is thus caused to firmly grip the wire *g*, the latter is prevented from being fed from the opening of the working head; but the other wire *g'* is fed into the operating-machine in the usual manner without obstruction and is forced into the stock, being properly cut off at each actuation of the machine.

When it is desired to convert the machine into a duplex nailing-machine, it is necessary to release the gripping device *d'*, and the result will be that both wires are simultaneously fed through the working head and into the stock. To do this I employ the following arrangement of mechanism: On the base *A'* of the machine I arrange a support *h*, provided with a horizontally-swinging knee-piece or other suitable operating device *h'*, which when

operated pulls on a chain or other flexible connection *i*, which is passed through an eye *j* on the bearing of the shaft *a*. (Shown in Fig. 1.) Said chain or flexible connection also passes through an eye *e'* in an extension *e³* on said arm *e* and is secured to a suitable crank-arm *e³*, pivotally arranged on a pin or screw on the face of the arm *e*, and when the flexible connection *i* is pulled it causes a slotted arm *e⁴* of said crank *e³* to be raised. On said arm *e* is a bearing *e⁵*, in which is pivotally arranged a suitable plate *e⁶*, having on its face a pin *e⁷*, which normally extends into the slot *8c* in said arm *e⁴*, and on its back are two other pins *e⁸* and *e⁹*, which extend into and through suitable openings in the arm *e*, as will be clearly seen from an inspection of Figs. 4 and 5. Now when the crank-arm moves on its pivotal support in the direction of arrow *E*, (see Fig. 5,) the slotted arm *e⁴* slightly tilts the pin *e⁷*, causing the plate *e⁶* to slightly rotate in its bearing *e⁵* and bring the pin *e⁸* from the position shown in Fig. 4 to the dotted position indicated in the same figure, while the pin *e⁹* moves in the direction of arrow *E'* in said figure. Said pin *e⁸*, now projecting farther from the back of the said arm *e*, it is brought in contact with a suitable projection *k* on the yoke *a⁷*. Said vibrating yoke rotates the spindle for about a quarter-turn, bringing said projection *k* against the pin *e⁸*, causing the two arms *e* and *f* to assume their buckled positions, (illustrated in Fig. 2,) in which positions they are retained as long as the chain or other flexible connection *i* is kept taut by means of the operated knee-piece *h*. When the two arms *e* and *f* have assumed these positions, the cam-shaped stop or nosing *f²* is released from its engagement with the side of the gripper or jaw *d³*, and the mechanism in the working head is now free to operate upon the wire *g*, drawing it through said gripping device *d'* without interference and being fed from the throat-piece of the working head by the action of the grippers therein.

The action of the grippers in the working head upon the wire *g* is such that when the gripping device *d'* is holding the wire said grippers in the working head will not interfere with the working of the other parts of the machine, while the other wire *g'* is fed into and passes through the working head in the usual manner.

When it is desired to again use the machine as a single nailing-machine, the operator releases the pressure from the knee-piece *h*, and the parts connected with the crank-arm *e³* on the face of the arm *e* assume their normal positions, (shown in said Figs. 4 and 5,) caused to do so partly by the action of the knee-piece *h* and the connecting-chain or connection *i* and a spring *e¹⁰* on said plate *e*, which exerts a pressure against the arm *e³*. On said vibrating yoke *a⁷* is a second projection *k'*, which during the quarter-turn of the parts is brought to the other side of the projecting end of the pin *e⁹*, engages therewith on its return, and

once more arranges the arms *e* and *f* in a straight line, as shown in Fig. 1, forming, practically speaking, a rigid piece, and causing the wire *g* to be again held in the jaws of the gripping device *d'*, at the same time lifting the wire *g* about one-quarter of an inch in the working head, while the other wire *g'* is fed from its throat into the stock to be nailed. When the arms *e* and *f* pass from their buckled positions (shown in Fig. 2) to their straightened positions, (indicated in Fig. 1,) it will be seen that the cross-head *d* slides upwardly in the frame *c*, and as soon as the cam-shaped jaw *f²* on the arm *f* causes the grippers *d'* to grip the wire *g* there will be sufficient upward movement of the parts to withdraw the free end of said wire *g* from the throat of the working head in the latter, so that it will not injure the stock placed under the working head of the machine when used as a single nailing-machine.

From the above description it will be seen that an operative device or mechanism has been constructed resulting in a nailing-machine which can be used as a single or duplex nailing-machine at the will of the operator. Said arms *e* and *f* being connected with a collar *a⁶* have an up-and-down movement, and the said yoke *a⁷*, provided with the projections *k* and *k'*, having a vibratory movement in a horizontal plane, said stops are brought on the opposite sides of the pins *e⁸* and *e⁹* and engage with the respective pins at the proper times to render the mechanism operative for the purposes for which it is intended, as will be clearly understood.

By my improvements I have devised a machine in which two separate fastening-wires differing from each other in size or in the shapes may be fed into the stock and cut-off simultaneously to form a duplex nailing-machine, or but one wire may be fed into the stock and cut-off, forming a single nailing-machine.

Having thus described my invention, what I claim is—

1. In a nailing machine of the class herein set forth, the combination, with the working head, and the vibrating yoke of the machine, of mechanism connected therewith for stopping the feeding of the wire through the working head and withdrawing the wire into the same, when stopping the feeding of the wire, substantially as and for the purposes set forth.

2. In a nailing machine of the class herein set forth, in combination with the working head, and the vibrating yoke of the machine, of a wire gripping or holding device and means for actuating the same to prevent the wire from being fed through the working head and at the same time withdrawing it into the same, substantially as and for the purposes set forth.

3. In a nailing machine, of the class herein set forth, the combination of the spindle and the collar of the driving sleeve, with a wire

gripper arranged to slide in a frame on said machine, and means connected with said collar of the driving sleeve and said gripper for operating the same, substantially as and for the purposes set forth. 7c

4. In a nailing machine of the class described, the combination, of the spindle and the collar of the driving sleeve thereon, with a wire gripper arranged to slide in a frame on said machine, an arm, as *e*, pivotally connected at one end with the collar of the driving sleeve on the spindle, an arm *f*, pivotally connected with said arm *e* and the said gripper, and mechanism on said arm *e*, for operating said arms *e* and *f* and releasing the jaws of the wire gripper, substantially as and for the purposes set forth. 75

5. In a nailing machine of the class herein set forth, the slide or cross head *d*, a pair of gripping jaws thereon, and the arms *e* and *f*, combined with a collar *a⁶* of the driving sleeve, and means, as set forth, to operate the same. 80

6. In a nailing machine of the class herein set forth, the combination, of the vibrating yoke *a⁷* having projections *k* and *k'*, with an arm *e*, means on said arm adapted to be engaged by said projections, a wire gripper arranged to slide in a frame in said machine, and an arm, as *f*, connected with said wire gripper and the said arm *e*, all arranged substantially as and for the purposes set forth. 95

7. In a nailing machine of the class herein set forth, the slide or cross head *d* having guides *d⁵*, a fixed gripping jaw and a movable jaw *d⁸* in said guides, an arm *f* having a cam-like extension, adapted to engage with said jaw *d⁸*, and an arm *e*, combined with the collar *a⁶* of the driving sleeve, and means for actuating said arms, substantially as and for the purposes set forth. 100

8. In a nailing machine of the class herein set forth, the combination of the vibrating yoke *a⁷* having projections *k* and *k'*, with an arm *e*, a spring-actuated crank arm pivotally arranged on said arm *e*, having a slotted arm *e⁴* for actuating said plate, and pins *e⁸* and *e⁹* on the back of said plate extending through 115 openings in the arm *e*, to be engaged by said projections, substantially as and for the purposes set forth.

9. In a nailing machine of the class herein set forth, the combination, of the vibrating yoke *a⁷* having projections *k* and *k'*, with an arm *e*, a spring-actuated crank arm pivotally arranged on said arm *e*, having a slotted arm *e⁴* for actuating said plate, and pins *e⁸* and *e⁹* on the back of said plate extending through 125 openings in the arm *e*, to be engaged by said projections, a frame, as *c*, a cross-head or slide in said frame provided with a wire gripper, an arm or link connecting said cross-head or slide and the one end of said arm *e*, all substantially as and for the purposes set forth. 130

10. In a nailing machine of the class herein set forth, the combination, of the vibrating yoke *a⁷* having projections *k* and *k'*, with an

arm e , a spring-actuated crank arm pivotally arranged on said arm e , having a slotted arm e^4 , a plate e^6 , having a pin extending into said slotted arm e^4 for actuating said plate, and pins e^8 and e^9 on the back of said plate extending through openings in the arm e , to be engaged by said projections, and means for operating said crank arm and the parts connected therewith, substantially as and for the purposes set forth.

11. In a nailing machine of the class herein set forth, the combination, of the vibrating yoke a^7 having projections k and k' , with an arm e , a spring-actuated crank-arm pivotally arranged on said arm e , having a slotted arm e^4 , a plate e^6 , having a pin extending into said slotted arm e^4 for actuating said plate, and pins e^8 and e^9 on the back of said plate extending through openings in the arm e , to be engaged by said projections, and means for operating said crank-arm and the parts connected therewith, consisting essentially, of a

pivoted knee-piece, as h , and a flexible connection between said knee-piece and said crank-arm, substantially as and for the purposes set forth.

12. In a nailing machine of the class herein set forth, arm e , crank arm e^3 thereon, having a slotted arm e^4 , a plate e^6 pivotally mounted in a bearing on said arm e , a pin on said plate extending into said slotted arm e^4 , and pins e^8 and e^9 on the opposite side of said plate extending through openings in said arm e , combined with a vibrating yoke a^7 , and means thereon, adapted to engage with said pins e^8 and e^9 , substantially as and for the purposes set forth.

In testimony that I claim the invention set forth above I have hereunto set my hand this 31st day of January, 1895.

GEORGE A. AMBLER.
